UNITED STATES PATENT OFFICE.

HERMANN V. LETKEMANN, OF NEW YORK, N. Y.

DESIGN FOR A RING OR BROOCH.

46,685.

Specification for Design.

Patented Nov. 24, 1914.

Application filed October 3, 1914. Serial No. 864,962. Term of patent 3½ years.

To all whom it may concern:

Be it known that I, HERMANN V. LETKEMANN, a citizen of the United States, and a resident of the borough of Manhattan, in the city, county, and State of New York, have invented a new, original, and ornamental Design for a Ring or Brooch, of which the following is a specification, reference being had to the accompanying drawing, forming a part thereof.

The figure is a front view of a brooch, showing my new design.

I claim:

The ornamental design for a ring or brooch, as shown.

HERMANN V. LETKEMANN.
